STRAIGHT-BAR KNITTING MACHINE

Harry Wilfred Start, Nottingham, England, assignor to George Blackburn and Sons Limited, Nottingham, England

Application September 4, 1936, Serial No. 99,473
In Great Britain September 3, 1935

4 Claims. (Cl. 66—82)

This invention relates to improvements in or applicable to straight-bar knitting machines of the "Cotton" type, and its object is to provide simple and convenient means for automatically controlling the operation of the machine, as is required to produce full fashioned and reinforced garments such for example as stockings, whereby the personal attention required and the manual adjustments which have to be made, are reduced to the minimum.

The major portion of the most important changes which have to be made, are effected by moving the antifriction rollers in connection with the operating cams laterally on the axles of the cam levers associated with the cams. The antifriction roller in connection with each cam is by this action transferred from the normal cam on to another one at the side of it, or transferred on to a plain disc. In one case the movements of the member in the machine actuated by the cam is modified, whilst in the other case the said member is left at rest. Certain adjustments have also to be made in the thread carrier mechanism from time to time, and these adjustments are at present mainly effected by hand.

The primary controlling mechanism usually employed consists of an endless chain fitted at intervals with rows of studs. This chain is mounted on sprocket wheels and is advanced by ratchet and pawl mechanism, whereby the studs in each row are caused to act on levers in succession, and effect through further mechanism, the adjustment of the various parts of the machine which are necessary at the correct periods in the course of knitting a garment.

This controlling mechanism is sometimes called the counting mechanism, as it effects each of the necessary changes after a predetermined number of courses have been knitted, and ensures that the whole of the garments produced are identical. The controlling mechanism described is in a machine which is only designed to knit stocking legs, adapted to effect all the necessary changes required, but in a machine which is adapted to knit a complete leg and foot, the changes that must be made to knit the foot are increased to such an extent that they cannot all be effected by the primary controlling mechanism, and secondary controlling mechanism must be provided which is to a certain extent controlled by the primary controlling mechanism. Various mechanical arrangements have been adopted for this purpose.

According to this invention the secondary controlling mechanism is electrical, and in order to obviate the necessity for the use of powerful electro-magnets, and a heavy current for energizing them where the power required to effect the necessary changes is considerable, such for example as that required to adjust the anti-fric-

tion rollers in connection with the operating cams on the main cam shaft, mechanical means which are controlled by electro-magnets are employed, and the arrangement constitutes an electro-mechanical unit which is provided in connection with each cam roller that has to be adjusted from time to time. Where on the other hand little power is required to effect the required adjustment, electro-magnets are used the armature of which may be directly connected to the member which has to be adjusted. The current is switched on to each of the electro-magnets employed at the proper time, by means of a current distributor which takes the form of a series of electrical switches, which are controlled by lifts on a drum, which latter is advanced at intervals by ratchet and pawl mechanism controlled by the primary controlling or counting mechanism, and each electro-magnet is thus excited and the necessary adjustment automatically made at the proper time during the course of knitting a garment.

The invention will now be particularly described with reference to the accompanying drawings, in which

Fig. 1 is a vertical section taken across a knitting machine of the "Cotton" type to which the invention is applied

Fig. 2 is a front elevation of part of the machine

Fig. 3 is a front elevation, and

Fig. 4 an end elevation of one of the electro-mechanical units which are employed.

Fig. 5 is a vertical cross section, and

Fig. 6 a front view of one end of the electric current distributing mechanism

Figs. 3 to 6 inclusive are drawn to a larger scale than Figs. 1 and 2.

Like letters indicate like parts throughout the drawings.

In carrying out this invention, the electric current distributing device consists of a series of switches A (see Figs. 5 and 6) which are controlled by a series of lifts B¹ arranged round the periphery of a drum B, and these lifts B¹ are adapted to close the switches A in the required order as the drum B is advanced. The switches A are disposed in the electric circuits of the electromagnets employed, and the said magnets are therefore controlled by the disposition of the lifts B¹ on the drum B, and the means which control its angular advancing movements.

The drum B is secured on an axle B² mounted in a casing B⁴ and is actuated by a pawl C (see Figs. 1 and 2) engaging with the teeth of a ratchet wheel B³ secured on the axle B². This pawl C which is carried by an arm C¹ mounted on the axle B², is controlled by a bluffing disc or member C², which is mounted on the axle B² and is adjusted so as to put the pawl C into and out of

action as required, by a connection with the primary controlling mechanism that will be herein-after described. The drum B is therefore mainly at rest, and is only advanced when a change has 5 to be made, and it will be understood that this drum B like the primary controlling mechanism, makes a series of advancing movements which are completed at the same time as those of the primary controlling mechanism, and is ready to 10 commence a repeat at the same time as the latter.

The arm C¹ which carries the pawl C is connected by a link C³ to a lever C⁴ which is actuated by a cam C⁵ on the cam shaft D. The blufing disc or member C² is on the other hand connected 15 to a lever E¹ associated with the primary controlling mechanism E by the following arrangement.

A shaft E² mounted in bearings in the fixed frame, is fitted with an arm E³ which engages with 20 the lever E¹ associated with the primary controlling mechanism E, and another arm E⁴ on this shaft E² is connected by a link E⁵ to the blufing disc or member C¹. The latter is thus adjusted by studs on the endless pattern chain which forms 25 the primary controlling mechanism E.

The employment of electro-magnets alone would necessitate the use of very powerful current to excite them and the current would have to be sustained for some time. There would also be the 30 risk of failure at times, as none of the movements would be positive, and in order to remove these objections, mechanical means associated with electrically operated magnets are employed.

Mechanical means may for instance be employed to move the required members from their 35 normal positions, and catches controlled by electro-magnets be employed for holding the required members in the new positions, but in the preferred arrangement which is shown in the drawings, the 40 reverse arrangement is adopted, that is, a mechanical arrangement which is adapted to effect the required movement is put into action by exciting an electro-magnet associated therewith, and the member when moved is then held by a 45 locking arrangement which is adapted to be released by putting the mechanical arrangement into action a second time, a result which is effected by exciting the electro-magnet again.

With this system, electro-mechanical units can 50 be provided to adjust each cam roller or other part which are not only compact, but can be disposed in a position where there is room for them, instead of being necessarily disposed close to the adjustable member which they control.

One of these units is shown detached in Figs. 55 4 and 5 and is constructed as follows:—

A shaft G which is mounted in bearings in the fixed frame and is permanently geared to and runs at the same speed as the main cam shaft D, is 60 fitted with a face cam H, and associated with this cam is a cam lever J which is adapted to move about and slide on a fixed shaft K, which latter is carried on the fixed frame above and parallel to the shaft G. The lever J can be turned about 65 the shaft K, in order to move the anti-friction roller J¹ on its lower end from its normal position in which it is shown, into the path of the cam rise H¹ on the side of the cam H. The lever J is for this purpose connected by an arm L¹ to 70 the armature L² of an electro-magnet L, so that when the latter is excited, the roller J¹ on the said lever J is adjusted in the path of the cam rise H¹, and the lever J is then consequently moved by the said cam H along the fixed shaft K, to 75 the right as seen in Fig. 3.

A second sliding member M is disposed on the fixed shaft K at the right of the arm J, and a rod M¹ is mounted loosely in its upper end and in the upper end of a fixed member M³ on the shaft K. The member M is connected to the fixed member M³ by a spring M⁴, and the member M is connected to the rod M¹ by a spring M². This member M and the rod M¹ are moved by the lever J against the action of the spring M⁴, and the rod M¹ which is connected as will be hereinafter described to 10 a cam roller, will move the latter from its normal position, but this movement is not positive, owing to the connection between the member M and the rod M¹ being only effected by the spring M², so that the timing of the said movement is not critical, as it would otherwise have to be, as there is only one position of the cams where the movement of the roller can be effected. With the arrangement described the movement can be started well in advance, and the spring M² will effect the 15 final movement of the cam roller as soon as the position of the cams will permit of this taking place.

As soon as the cam rise H¹ on the cam H has 20 moved clear of the roller J¹ on the lever J, the current can be cut off from the electro-magnet L, and the said roller thereon is then moved clear of the cam H by a spring J² whilst the member M and rod M¹ are retained in the position to 25 which they have been moved by the cam H, by 30 means of a locking arrangement which will now be described.

Secured to the fixed shaft K is a locking plate N with an upper race N¹ and a lower race N², which latter starts out of the upper race N¹ at the 35 end of the latter which is nearest to the member M. The other ends of the two races are connected by an inwardly curved part N³, and a pivoted switch N⁴ which is actuated by a spring N⁵ is disposed at the junction of the two races, and this switch N⁴ normally closes the entrance to the lower race N².

Above the locking plate N described is a fixed pivot O which is carried by a bracket O¹ secured on the fixed shaft K, and a locking member P with a stud P¹ at its lower end and a slot P² at its upper end, is disposed with the stud at its lower end normally in the near end of the upper race N¹ in the locking plate N, and its upper slotted end on the fixed pivot O. An intermediate point 45 in the locking member P is connected by means of a link P³ to the member M, and one end of a spring P⁴ is connected to the locking member P and tends to pull it down. The other end of the 50 spring P⁴ is connected to the locking plate N. 55

The action of this arrangement is as follows:— When the member M is moved to the right as previously described, the stud P¹ at the lower end of the locking member P travels along the upper race N¹ in the locking plate N, until it reaches the outer end, and it is then drawn down into the inwardly curved part of the race N³ by the action of the spring P⁴ on the member P and the spring M⁴ which tends to return the member M back to its normal position. The stud P¹ is then held in the said curved race N³ by the action of the two springs P⁴ and M⁴ and locks the member M and the rod M¹ in the position to which they have been moved by the cam H.

In order to release the member M, the electro-magnet is excited again so as to bring the roller J¹ on the cam lever J into the path of the cam H again, and the said lever J and member M are then moved far enough to the right to cause the 70 75

stud P¹ on the locking member P to move down into the lower race N² in the locking plate N, and the stud P¹ is then free to travel back along this lower race N² when the cam lever J is released by the cam H, and further permits of the return of the member M at the same time, a result which is effected by the spring M⁴. The stud P¹ on the member P is on its outward movement directed along the upper race N¹ in the locking plate N by the pivoted switch N⁴, and the latter is tripped by the stud P¹ when it returns along the lower race N².

The return movement of the member M also effects the return movement of the rod M¹ as it then engages with a collar M⁵ fixed on the said rod.

The rod M¹ is as shown in Figs. 1 and 2 connected by means of a bracket Q¹ to a rod Q which is carried along the front of the machine in guide plates Q² and this rod is fitted with an arm Q³ which engages with the anti-friction roller KQ⁴ on the cam lever Q⁵, and the movement obtained from the electro-mechanical unit described, is thus transmitted to and adapted to adjust the said roller Q⁴ in register with either one or the other of the two cams Q⁶ shown in Fig. 2.

Only one electro-mechanical unit and one cam roller is shown, but it will be understood that a similar arrangement will be provided in connection with each cam roller or other part which has to be adjusted, and that the adjustment of each is effected by exciting the corresponding electro-magnet and is automatically effected by the action of the current distributing arrangement previously described.

The advantages of the arrangement described are that only a moderate current is required to excite the electro-magnets, and this current is only on for a short time, so that not only is the current consumption very slight, but the electro-magnets do not become overheated. The electro-mechanical units can be disposed in a convenient position and the rod M¹ associated with each can be connected to its cam roller for instance by a longitudinal rod carried through the guide plates Q² in the same manner as the arrangement shown.

What I claim is:—

1. In a straight-bar knitting machine, electro-mechanical means for automatically adjusting a cam roller or other adjustable part comprising in combination, a cam on a running shaft, a cam lever which can slide on its pivot and is also adjustable about the said pivot in order that its anti-friction roller which is normally clear of the cam can be moved into the path of the latter, an electro-magnet for effecting this movement when excited, a supplementary member which is moved at the same time as the cam lever, means for connecting this supplementary member to a cam roller or other member to be adjusted, means which are adapted to hold the secondary member in the position to which it is moved by the cam and subsequently releasing it by a second movement of the cam lever, and means for switching the current on to the electro-magnet at the required periods, substantially as described.

2. In a straight-bar knitting machine, electro-mechanical means for automatically adjusting a cam roller or other adjustable part comprising

in combination, a cam on a running shaft, a cam lever which is slideable on and also adjustable about its axle, an electro-magnet for moving the cam lever about its axle so as to adjust its anti-friction roller in the path of the cam, a supplementary member on the cam lever axle which is moved at the same time as and by the cam lever, means for connecting this supplementary member to the cam roller or other adjustable member, means for holding the supplementary member in the position to which it is moved by the cam consisting of a locking member which is connected to the supplementary member and has its upper slotted end working on a fixed pin and a stud at its lower end working in upper and lower races in a fixed locking plate so disposed that the stud moves along one race and is then held until it is directed into the lower race by a second movement of the supplementary member, and means for switching the current on to the electro-magnet at the required periods, substantially as described.

3. In a straight-bar knitting machine, electro-mechanical means for automatically adjusting a cam roller or other part in a machine comprising in combination, a cam on a running shaft, a cam lever which can slide on and also turn about the axle on which it is disposed and is normally inoperative, an electro-magnet which has its armature connected to the said cam lever and is adapted when excited to adjust the roller on the said lever in the path of the cam so that it is moved along its axle, a spring returned supplementary member which is disposed at the side of and is moved by the cam lever, non-positive means for connecting the supplementary member to the cam roller or other adjustable part, a locking member to which the supplementary member is connected by a link and said member having a slotted end which is disposed on a fixed pivot and a stud at its other end, a locking plate with upper and lower races in which the said stud works, said races both starting from one point and having their outer ends connected, by an inwardly curved part which holds the stud, a switch at the start of the lower races so as to direct the stud into the upper race, a spring connected to the locking member which tends to move the stud out of the curved part into the lower race when the locking member is actuated a second time, and means for switching the current on to the electro-magnet, substantially as described.

4. In a straight-bar knitting machine, the combination of a series of electro-magnets for controlling the adjusting movements of certain adjustable members in the machine, electric switches disposed in the circuits of the said magnets, a drum with lifts disposed thereon for closing the switches in the required order, a ratchet wheel on the axle of the said drum, a pawl for advancing the said ratchet wheel, means for actuating the said pawl, a bluffing member at the side of the ratchet wheel for controlling the pawl, and means for connecting this bluffing member to a lever which is actuated by studs on the pattern chain which comprises the primary controlling mechanism so that the latter controls the advancing movements of the switch closing drum, substantially as described.

HARRY WILFRED START. 70
